UNITED STATES PATENT OFFICE.

GEORGE BRAND, OF BROOKLYN, NEW YORK.

SUCTION-HEAD CONNECTION.

1,136,889.

Specification of Letters Patent. Patented Apr. 20, 1915.

Application filed July 24, 1914. Serial No. 852,886.

To all whom it may concern:

Be it known that I, GEORGE BRAND, a citizen of the United States, residing at Brooklyn, in the county of Kings and State of New York, have invented new and useful Improvements in Suction-Head Connections, of which the following is a specification.

This invention relates to an improved suction head connection of the hinged or flexible type for vacuum cleaning machines, and has for an object to provide a connection admitting of the automatic adjustment of the suction head to variations in the surface being cleaned and to the movements of the body of the machine; and a connection which limits the swinging of the suction head to maintain it in proper position on the machine at all times.

Another object of the invention is to provide a connection of this character admitting of the substitution of a flexible hose or tube in lieu of the suction head to thus adapt the connection to vacuum cleaning machines wherein hand tools are employed.

The above and other objects and advantages of this invention will be more clearly brought out from the following detail description of the present preferred embodiment of this invention which is illustrated in the accompanying drawing wherein,

Figure 1 is a side elevation of the forward end of a vacuum cleaning machine having the improved nozzle connection applied thereto. Fig. 2 is a top plan view of the same with the bellows removed. Fig. 3 is a central vertical section taken through the connection. Fig. 4 is a detail inner end view of the shank of the tool comprising one member of the connection. Fig. 5 is a top plan view of the tool support disclosing a flexible hose or tube applied thereto.

Referring to this drawing, wherein like parts are designated by similar characters of reference throughout the several views, 45 10 designates the body of a vacuum cleaning machine of any suitable type, provided upon its upper side with an operating bellows 11. A dust tube 12 is arranged beneath the body 10 and projects forwardly 50 therefrom, the forward end of the tube 12 being open and curved upwardly as shown at 13 in Figs. 1 and 3. The body 10 is pro-

vided at its opposite sides with a pair of brackets 14, the outer ends of which carry transversely alining bearings 15 receiving therethrough an axle 16. Wheels 17 are mounted upon the opposite ends of the axle 16 to support the forward end of the body 10 and have suitable connection, as by means of a pitman connection 18, with the bellows 11 to operate the latter.

Hinged upon the axle 16 between the brackets 14 is a head support 19 preferably of yoke-form, the opposite arms thereof having therein bearings 20 engaging the axle 16. The bearings 15 of the brackets are provided at one side with stop shoulders 21 lying in the path of abutment shoulders 22 carried upon the bearings 20 of the support. The shoulders 21 and 22 are adapted to limit the downward swinging of the support 19. The brackets 14 are provided with webs or shoulders 23 located in the path of the abutment shoulders 22 and arranged substantially at ninety degrees upon the bearings 15 from the stop shoulders 21, and rearwardly thereof. These webs or shoulders 23 are adapted for contact with the abutment shoulders 22 for the purpose of limiting the upward swinging of the support 19. A suitable suction head 24 is employed which is provided at its inner end with laterally extending lugs 25 through which pass thumb screws 26 for engagement in the support 19.

From Fig. 2, it will be noted that the lugs 25 incline inwardly toward the body 10 at a slight angle and lie snug against the correspondingly formed outer face of the support 19. The support 19 is provided, as shown in Fig. 3, with a through port 27 communicating with the suction head 24. The support 19 comprises, practically, a continuation or a part of the suction head and is provided with a downwardly and rearwardly curved shank 28 telescoping into the forward open end 13 of the dust pipe. The shank 28 and the end 13 are curved concentric to the axle 16 to provide a pivot for the telescoping parts, so that the same may be moved freely one within the other without binding.

From Figs. 3 and 4 it will be noted that the shank 28 is provided upon its open end

with a packing ring 29 clamped against the end by a metallic clamping ring 30. The clamping ring 30 is suitably held against the open end of the shank 28 by screws 31 or the like, the screws passing through the packing ring 29 and into the walls of the shank 28. The packing ring 29 and the clamping ring 30 are provided with central openings corresponding in size to the opening of the shank 28 to thus prevent any restricted portions or dust collecting shoulders within the connection.

In Fig. 5 the tool 24 is replaced by a nipple 24^a, the same being held against the support 19 by the thumb screws 26. The nipple 24^a is adapted to receive the inner end of a flexible pipe or tube 32 to which may be attached a hand tool (not shown) in the usual manner.

20 In operation the body 10 is supported upon the wheels 17 and is moved forwardly in any convenient manner. The wheels turn and operate the bellows 11 to create a suction through the body 10 and dust tube 12. 25 The suction head 24 rests against the surface to be cleaned and is held thereagainst by its own weight, the head 24 swinging about the axle 16 as a pivotal support. As the shank 28 and the curved end 30 are concentric with 30 the axle 16 the connection admits of the free swinging movement of the head to take up unevenness in the surface cleansed, or vibrations of the body during the operation of the machine. The packing 29 carried by the shank 28 bears against the inner wall of the curved end 13 and thus effectually seals the connection so that the suction through the head 24 is not destroyed.

By constructing the suction head so that 40 it may swing about a horizontal axis, and by having the shank on the support and the end of the dust tube both concentric with the axis free movement of the various parts is provided and by providing the telescoping parts with the packing an effective seal is formed which does away with all flexible couplings wherein tubes and the like have heretofore been employed.

It is, of course, understood that various 50 minor changes may be made in the details of the structure without departing from the spirit of the invention and within the scope of the following claims.

I claim,

55 1. In a vacuum cleaning machine, a relatively fixed dust tube, a pivotally mounted suction head support adapted for swinging movement in a vertical direction, a suction head secured to said support and having one end thereof adapted to freely rest upon the surface to be cleaned, a hollow shank on said support communicating with said head and telescoping into said tube and adapted for movement therein with the suction head.

2. In a vacuum cleaning machine, a dust tube having an open curved end, a pivotally mounted support, a suction head secured to said support at one end and having the other end adapted for free movement in a vertical direction whereby the same may rise and fall with the variations in the surface to be cleaned, a curved hollow shank on said support communicating with said head and engaging in said open end of the tube.

3. In a vacuum cleaning machine, a body, a dust tube fixed upon the body and having a curved open end, a bracket on the body, and a suction head support hinged upon the bracket concentric with the curved end of said tube and having a correspondingly curved hollow shank telescoping into said curved end of the tube, whereby to establish communication between the suction head support and the tube.

4. In a vacuum cleaning machine, a body, a dust tube fixed upon the body, a suction head support hinged upon the body and having a hollow shank telescoping into said tube, a suction head carried by said support, said dust tube and said shank being concentric to the pivotal support of said head.

5. In a vacuum cleaning machine, a body, a dust tube fixed upon the body and having a curved open end, a support hinged upon the body concentric to said curved end and having a hollow shank of corresponding curvature telescoping into said end, and a cleaning tool communicating with said support.

6. In a vacuum cleaning machine, a body, an axle on the body, a suction head support hinged upon the axle and having abutment shoulders, spaced apart stop shoulders carried by the body for engagement with said abutment shoulders to limit the swinging movement of the support, a dust tube on the body, and a hollow shank on said support engaging in said dust tube and adapted for sliding movement therein upon the movement of the support.

7. In a vacuum cleaning machine, a body, an axle on the body, a suction head support hinged upon the axle and having a hollow shank curved concentric to the axle, a dust tube on the body having a correspondingly curved open end receiving said shank, and stops upon the body and the support adapted to limit the swinging movement of the latter.

8. In a vacuum cleaning machine, a body, a rigid dust tube on the body, a suction head support hinged on the body having a rigid hollow shank adapted for sliding movement within said dust tube whereby to admit of the free movement of the support.

9. In a vacuum cleaning machine, a body, a dust tube, a vertically swinging support

freely hinged upon the body, an outwardly extending suction head connected to said support and having the free end thereof adapted to rest freely upon the surface to be cleaned, a hollow shank on said support engaging with the dust tube and a packing between the tube and the shank.

In testimony whereof I have hereunto set my hand in presence of two subscribing witnesses.

GEORGE BRAND.
